DESIGN FOR A PORTABLE HUMIDIFIER

Ralph E. Kruck, Springfield, and Paul E. Hochstetter, East Springfield, Mass., assignors to Westinghouse Electric and Manufacturing Company, a Corporation of Pennsylvania

Application June 2, 1933. Serial No. 48,264

Term of patent 7 years

To all whom it may concern:

Be it known that we, RALPH E. KRUCK and PAUL E. HOCHSTETTER, citizens of the United States, residing respectively, at Springfield, in the county of Hampden and State of Massachusetts; and East Springfield, in the county of Hampden and State of Massachusetts, have invented a new, original, and ornamental Design for Portable Humidifiers, of which the following is a specification, reference being had to the accompanying drawing, constituting a part thereof.

Figure 1 is a view in front elevation of a portable humidifier showing our new design, and Fig. 2 is a top plan view thereof.

We claim:

The ornamental design for a portable humidifier substantially as shown.

In testimony whereof, we have hereunto subscribed our names this 11th day of May, 1933.

RALPH E. KRUCK.
PAUL E. HOCHSTETTER.
